FILTER PROTECTION

Clarence W. Nessell, Dayton, Ohio, assignor to
 Minneapolis-Honeywell Regulator Company,
 Minneapolis, Minn., a corporation of Delaware

Application February 11, 1938, Serial No. 189,984

11 Claims. (Cl. 126—110)

The present invention relates generally to warm air heating systems and pertains more particularly to the elimination of the fire hazard attendant to the use of combustible air filters in such systems.

In present warm air heating systems, it is customary to employ filters to remove foreign matter such as dust and dirt and the like which may contaminate the air in rooms being heated and be carried into the return air registers. Fans are employed to provide an enforced circulation of air and inasmuch as the trend in furnace design is toward compactness, the filters are usually located in the return air section of the furnace which houses the fan as well. Filters as ordinarily used are made of combustible material and become coated with inflammable dust and debris and being located in close proximity to the furnace proper there is grave danger of their becoming ignited and setting the building on fire. The existence of this danger is plain and its seriousness is apparent inasmuch as the return air ducts frequently are formed in part from the wooden joists and flooring of frame buildings. The danger of igniting the filters and consequent fire hazard to the building is particularly serious when an "economizer" or a "preheater" is used. The "economizer" consists of a tortuous passageway for conveying gases of combustion to the stack or flue and is located in the path of the return air for the purpose of preheating same. The "economizer" normally becomes quite hot and in compact furnace designs is located close to the filters and increases the danger of setting the filters on fire. The danger is especially present when the furnace fan is not operating.

The primary object of my invention is to eliminate the above described fire hazard by providing means to limit the value to which the temperature adjacent the filters in a warm air heating system may rise.

Another object of my invention is to provide a positive acting device for automatically moving the filters in such a manner as to preclude their becoming ignited when such danger exists.

In connection with the previously stated object, it is a further object of the invention to cause the furnace fan to become automatically energized when danger of ignition of the filters occurs. The enforced circulation of air produced by the fan will operate to carry heat from the filters tending to reduce their temperature.

A further object of my invention is to provide a filter device automatically operable to move

substantially out of the air stream and the path of radiant heat flow from the furnace or "economizer" when danger of ignition occurs. The accomplishment of this objective results in the obstruction to the air stream formed by the filters being removed and the heating of the filters due to radiation from the furnace and economizer being greatly decreased.

A still further object of my invention is to provide a collapsible filter arrangement normally held in position by springs and a fusible link operative to collapse in response to a predetermined temperature causing said link to fuse.

Further objectives and purposes of the invention will become apparent from a perusal of the drawing and the more detailed description following.

The single figure represents somewhat diagrammatically the principal portions of a warm air heating system having an oil fired furnace controlled primarily by a room thermostat, and my improved filter protection and control arrangement incorporated therein.

Referring to the drawing, reference numeral 10 indicates generally a furnace casing forming a part of a warm air heating system. Casing 10 is divided into three separate compartments numbered 11, 12, and 13, compartment 12 being the heating chamber and compartment 13 forming a return air chamber. Conduits 14 and 15 communicate with compartments 12 and 13, respectively, for conveying heated air from the furnace to the spaces to be heated and back to the furnace. Conduits 14 and 15 may have branch conduits as shown at 16 and 17 for conveying air to and from individual rooms of a building being heated.

Compartment 11 of the furnace casing houses an oil burner of conventional type indicated at 20, the nozzle of which extends through the compartment 12 into the combustion chamber proper indicated at 21. The burnt gases of combustion from the chamber 21 pass through a device indicated at 22 commonly known as an economizer. The economizer 22 comprises a casing having an arrangement of internal baffles as shown whereby a tortuous passageway is formed for the gases as they pass to the stack or flue at 23. The economizer 22 is located within the return chamber 13 so that the return air passes in heat exchange relation with the economizer and is therefore preheated before being passed through the heating chamber proper 12. At the lower part of the return air chamber 13 is a fan or blower 25 of conventional type driven by an electric motor 26.

by means of a belt 27 or other suitable driving means. The fan 25 within the chamber 13 forces air through a discharge conduit 28 into the heating chamber 12 and past the furnace or combustion chamber 21.

Within the upper portion 30 of the return air chamber 13 is a series of filter members 31 arranged in the path of the return air stream for the purpose of removing any foreign matter with which the air being circulated may have become contaminated in the rooms being heated. The filter members 31 include two outer members hinged at points 32 and having their inner edges biased towards the side walls of the portion 30 of the chamber 13 by tension springs 33. The two inner members 31 are secured to a hinge member 35 which is rigidly pivoted at 36. The upper edges of the two inner members 31 may engage with angle members 37 attached to the upper edges of the outer members 31 as shown. The tension spring 40 tends to draw the inner member 31 towards each other around the pivot point 36 but it is prevented from doing so by reason of their engagement with the angle members 37. It is obvious that should the tension springs 33 be permitted to draw the outer members 31 toward the side walls of the chamber 13, the two inner members 31 will be drawn together by the spring 40. The filter members are retained in the position shown by means of links 41 which are pivoted to the outer members 31 and which engage at their lower ends with the horizontally arranged links 42. The links 42 are constrained to move in a horizontal direction by retaining elements 43 and are each biased towards the side walls of the chamber 13 by tension springs 44. The inner ends of the link members 42 are connected by a fusible link 45 which will fuse at a predetermined temperature in the region adjacent to the filter members and the fusible link. It is obvious that when the fusible link 45 fuses, the tension springs 44 will draw the links 42 outwardly freeing them from engagement with the links 41 and will thus permit tension springs 33 to disengage the outer members 31 from the inner members 31 and draw them towards the side walls of the chamber 13. When this happens, the tension spring 40 will draw the upper edges of the inner members 31 together thus causing all of the filter members to be substantially drawn out of the air stream. This collapsible arrangement of the filters is an important feature of the present invention inasmuch as the filters automatically collapse and remove themselves from the path of radiant heat from the economizer 22 at a predetermined temperature at which there is danger of their becoming ignited.

The link 42 on the left, as seen in the drawing, is connected as shown to a lever 50 carrying a double ended mercury switch 51. Normally, the mercury switch 51 is in the position shown in the drawing. Obviously, when the fusible link 45 fuses, tension spring 44 attached to the link 42 on the left will cause lever 50 to be rotated counterclockwise and will cause the contacts in the left end of the mercury switch 51 to be made and those in the right end of the switch to be broken.

The system is primarily controlled by a room thermostat generally indicated at 55. This thermostat comprises a circularly arranged bimetallic element 56 of conventional type having a movable arm 57 arranged to make or break an electrical circuit through a fixed contact 58. Further control is provided by a pair of mercury

switches 60 and 61 operated by a helical thermostatic element 62 responsive to the temperature of the air being heated within the chamber 12. The thermostatic element 62 is arranged to close the switch 61 at a predetermined relatively low temperature in the chamber 12 and to open the switch 60 which is normally closed at a predetermined relatively high temperature in the chamber 12 beyond which it is not desired that the temperature should rise.

Power for the system is supplied through a pair of line conductors 70 and 71 connected to an external source of power (not shown). The burner 20 is driven by an electric motor and energy for the motor is supplied through a wire 15 72, a wire 73, wire 74 connecting to a pilot controlled safety device 75, a wire 76 connecting to the mercury switch 60, a wire 77 connecting mercury switch 60 to the thermostatic switch 55, a wire 78 connecting the thermostatic switch to the right end of mercury switch 51, and a connection from the right end of mercury switch 51 to the line conductor 70. The pilot controlled safety device 75 is of conventional type and comprises a bimetallic element 80 arranged adjacent the pilot burner 81 so as to complete its circuit through the fixed contact 82 at all times when the pilot flame is burning. A pipe 83 communicates with the source of combustible gas providing fuel for the pilot flame 81 which is kept constantly burning for purposes of igniting fuel injected into the combustion chamber through the nozzle of burner 20. The extinguishment of the pilot flame 81 obviously causes the power supply circuit for the burner motor to be broken.

Power for the fan motor 26 is supplied from line conductor 71 through a conductor 72 to the motor, a wire 85 from the motor to the mercury switch 61, and a wire 86 from the mercury switch 61 to the line conductor 70. Obviously, whenever the mercury switch 61 is closed the fan motor 26 will be energized and the fan 25 enforces a positive circulation of air through the system. The fan motor 26 may also be energized when the mercury switch 51 is tilted to the left by a circuit 45 from line conductor 70 through the left end of the mercury switch 51 to a wire 88, through the wire 85, through the motor and through wire 72 back to the line conductor 71.

From the foregoing description the operation 50 of my system and the manner of control should be apparent to those skilled in the art. With the parts in the position shown in the drawing, the thermostat is satisfied and neither the burner 20 nor the fan motor 26 are operated. Should 55 the room or space temperature fall to a predetermined value indicating that heat should be supplied to the spaces being heated, the thermostatic switch device 55 closes completing the above described electric circuit through the 60 burner motor. When the temperature within the heating chamber 12 has risen to a predetermined value, mercury switch 61 will close, energizing the motor 26 causing the fan 25 to begin 65 positively circulating air through the system. It will be seen that this air is drawn through the filter members 31 and is preheated as it passes over the economizer 22 before being forced into the heating chamber 12. The economizer temperature may rise to a relatively high value and considerable heat is radiated therefrom which is normally imparted to the air being circulated past the economizer. Should the fan 25 now 70 stop due to breakage of the belt 27, or if the temperature adjacent the filter should for any other 75

- reason rise to a predetermined value at which there is danger of igniting the filter material, the fusible link 45 fuses. When this happens, the filter members 31 collapse in the manner above described and at the same time the mercury switch 51 is tilted to the left breaking the electrical circuit through the burner motor and at the same time completing a circuit through the left end of the mercury switch to the fan motor. At times, the temperature adjacent the filter members 31 may rise to an unsafe value before the temperature in the heating chamber 12 has risen to a high enough value to cause closure of switch 51. The fan 25 will therefore not be operating at the time fusion of link 45 takes place. However, in any system by reason of the double ended mercury switch 51, operation of the fan will be initiated at this time and will operate to positively circulate air over the economizer 22 and will tend to diminish its temperature. In practice, filter members such as the members 31 as ordinarily employed present considerable surface to exposure from radiant heat from the economizer and thus as the economizer temperature rises the filter temperature rises accordingly. By my collapsible arrangement of the filter members, their surfaces are automatically removed from exposure to radiant heat from the economizer and they are positioned so as not to obstruct the passage of air over the economizer. The double ended mercury switch 51 provides an additional safety feature which eliminates the danger of combustion taking place in the filters in the event that the economizer should reach an unsafe temperature value before operation of the fan 25 has begun. My improved arrangement eliminates a serious fire hazard attendant to the use of filters especially when employed in compact furnace designs as at present in use. Its simplicity and sturdiness make its use very economical and additionally, being easy of installation, it is an appliance which may be universally utilized in present existing warm air heating systems.
- While one embodiment of the invention has been disclosed, there are many variations and modifications and forms which the invention may take and it is to be understood that the present disclosure is to be interpreted as illustrative only and the scope of the invention to be limited only as determined by the appended claims.
- I claim as my invention:
1. In a warm air heating system, in combination, heating means, means for circulating air to be heated past said heating means, filter means for cleaning said air exposed to heat from said heating means, said filter means being collapsible supported and normally latched in non-collapsed position by means including a temperature responsive element so arranged that at a predetermined temperature adjacent said filter means the filter means will be automatically removed from exposure to heat from said heating means whereby danger of ignition of the filter means is eliminated.
  2. In a heating system, in combination, a heater, means for circulating air to be heated past said heater, collapsible filter means for cleaning said air exposed to radiant heat from said heater, means including spring latches and a temperature responsive element adjacent filter means for causing said filter means to collapse substantially out of the path of radiant heat from said heater at a predetermined temperature of said temperature responsive element.
  3. In a heating system, in combination, a heater, means for circulating air past said heater, filter means for cleaning said air exposed to heat from said heater, said filter means comprising hinged portions retained in position by means including spring members and a fusible link, said link being located adjacent said filter means said filter means being arranged to move in such a way as to expose insubstantial surface to heat from said heater at a predetermined temperature causing said link to fuse.
  4. In a heating system in combination a furnace having a casing, means for circulating air to be heated through said casing, filter means for cleaning air located in said casing adjacent a part of said furnace and exposed to radiation of heat from said furnace part, means including a temperature responsive element adjacent said filter means for abruptly moving said filter means substantially out of the path of heat radiated from said furnace part at a predetermined temperature affecting said temperature responsive element.
  5. In a heating system, in combination, a furnace having a casing, a fan for circulating air to be heated through said casing, filter means for cleaning said air located in a part of said casing exposed to heat from said furnace, means operable at a predetermined temperature adjacent said filter means for substantially removing them from exposure to heat from said furnace and for simultaneously starting said fan for circulating air past said filter means.
  6. In a heating system, in combination, a furnace having a casing, a fan for circulating air to be heated through said casing, filter means for cleaning air located in a part of said casing exposed to heat from said furnace, means operable at a predetermined temperature adjacent said filter means for substantially removing them from exposure to heat from said furnace, and means actuated upon removal of the filter means for starting said fan and cutting off the heat supply to said furnace.
  7. In a heating system, in combination, a furnace including a casing having a return air chamber, an economizer comprising a tortuous passageway for burnt gases of combustion in said return air chamber, means for circulating air through said casing over said economizer and filter means for cleaning said air located adjacent said economizer, said filter means comprising a collapsible arrangement of hinged members, means for retaining said filter means in normal position comprising spring members and a fusible link adjacent said filter means, said retaining means being arranged to cause said hinged members to collapse to protect them from radiant heat at a predetermined temperature causing said link to fuse.
  8. In a heating system, in combination, a furnace including a casing having a return air chamber, an economizer comprising a tortuous passageway for burnt gases of combustion in said return air chamber, means for circulating air through said casing over said economizer and filter means for cleaning said air located adjacent said economizer, said filter means comprising a collapsible arrangement of hinged members, means for retaining said filter means in normal position comprising spring members and a fusible link adjacent said filter means, said retaining means being arranged to cause said

hinged members to collapse to protect them from radiant heat at a predetermined temperature causing said link to fuse, and switch means operable upon fusion of said link to start said air circulating means and to cut off the heat supply to the furnace.

9. In a heating system, in combination, heating means, means for circulating air to be heated over said heating means, filter means for cleaning air normally exposed to heat from said heating means, said filter means being susceptible to becoming overheated and being substantially removable from exposure to heat from said heating means, and means responsive to a condition indicating that said filter means may become overheated for abruptly and substantially removing said filter means from exposure to heat from said heating means.

10. In a heating system, in combination, heating means, means comprising a fan for circulating air to be heated over said heating means, filter means for cleaning air normally exposed

to heat from said heating means, said filter means being susceptible to becoming overheated and being substantially removable from exposure to heat from said heating means, and means responsive to a condition indicating danger that said filter means may become overheated for substantially removing said filter means from exposure to heat from said heating means, and for causing operation of said fan for transporting heat away from the vicinity of said filter means.

11. In a heating system, in combination, heating means, means for circulating air to be heated over said heating means, filter means for cleaning air having a normal position exposed to heat from said heating means, said filter means being susceptible to becoming overheated, means comprising a fusible link whereby at a predetermined temperature causing said link to fuse, said filter means are substantially removed from exposure to heat from said heating means.

hinged members to collapse to protect them from radiant heat at a predetermined temperature causing said link to fuse, and switch means operable upon fusion of said link to start said air circulating means and to cut off the heat supply to the furnace.

9. In a heating system, in combination, heating means, means for circulating air to be heated over said heating means, filter means for cleaning air normally exposed to heat from said heating means, said filter means being susceptible to becoming overheated and being substantially removable from exposure to heat from said heating means, and means responsive to a condition indicating that said filter means may become overheated for abruptly and substantially removing said filter means from exposure to heat from said heating means.

10. In a heating system, in combination, heating means, means comprising a fan for circulating air to be heated over said heating means, filter means for cleaning air normally exposed

to heat from said heating means, said filter means being susceptible to becoming overheated and being substantially removable from exposure to heat from said heating means, and means responsive to a condition indicating danger that said filter means may become overheated for substantially removing said filter means from exposure to heat from said heating means, and for causing operation of said fan for transporting heat away from the vicinity of said filter means.

11. In a heating system, in combination, heating means, means for circulating air to be heated over said heating means, filter means for cleaning air having a normal position exposed to heat from said heating means, said filter means being susceptible to becoming overheated, means comprising a fusible link whereby at a predetermined temperature causing said link to fuse, said filter means are substantially removed from exposure to heat from said heating means.
